UNITED STATES PATENT OFFICE.

CARL WILMSHÖFER, OF ERFURT, GERMANY.

STIFFENING-CAP FOR SHOES.

No. 853,140.

Specification of Letters Patent.

Patented May 7, 1907.

Application filed May 21, 1906. Serial No. 318,021.

To all whom it may concern:

Be it known, that I, CARL WILMSHÖFER, manufacturer, a subject of the King of Prussia, residing at Erfurt, Kingdom of Prussia, 5 German Empire, have invented certain new and useful Improvements in Stiffening-Caps for Shoes, of which the following is a specification.

My invention relates to improvements in 10 stiffening cap for shoes.

The characteristic feature of the stiffening cap for shoes according to this invention consists in the fact that the material of the cap is partly penetrated by a layer of rubber 15 placed on it. In this way, the cap, on the one hand, remains elastic and flexible, and, on the other hand, has sufficient stiffness and therefore retains permanently the shape given to it. The rubber layer, partly penetrating the material of the cap, also enables 20 a layer of canvas to be put on and securely held.

Two different constructions of the cap according to this invention are illustrated 25 in the accompanying drawing.

Figures 1 and 2 are respectively an elevation and cross-section of one construction, and Figs. 3 and 4 an elevation and cross-section of another construction.

30 The leather 1 is provided with a number of perforations 2 through which passes the rubber layer 3. The side of the leather 1

opposite the rubber layer 3, is provided with a canvas backing 4 which is secured in a reliable manner owing to the connection with 35 the rubber layer 3 passing through the openings 2 of the leather 1.

The construction in Figs. 3 and 4 is similar to that shown in Figs. 1 and 2, only the leather 1 is cut out at the back at 5, so that the 40 leather portion has the form of an arc. At the part where the leather is cut away, the corresponding portion of the cap is constituted by the rubber layer 3 and the canvas 45 layer 4. The openings 2 are arranged in the leather 1 in the same way as in the construction shown in Figs. 1 and 2.

It is immaterial what size and shape is given to the cap.

What I claim is:

A stiffening cap for shoes comprising a 50 perforated stiffening member and an elastic member having flexible projections extending into said perforations, and a backing secured to said stiffening member and projections.

In testimony whereof I have hereunto set my hand in presence of two subscribing witnesses.

CARL WILMSHÖFER.
